UNITED STATES PATENT OFFICE.

STEPHEN B. MORSS, OF RAIHWAY, NEW JERSEY, ASSIGNOR OF ONE-FOURTH
TO CHARLES C. MICKLE, OF NEW YORK, N. Y.

LAMP-WICK.

SPECIFICATION forming part of Letters Patent No. 555,257, dated February 25, 1896.

Application filed April 11, 1895. Serial No. 545,276. (No model.)

To all whom it may concern:

Be it known that I, STEPHEN B. MORSS, a citizen of the United States, residing in Rahway, Union county, New Jersey, have invented 5 certain new and useful Improvements in Lamp-Wicks, of which the following is a specification.

The object of my invention is to provide a practically non-combustible wick which shall 10 possess all the advantageous oil-feeding qualities of the ordinary cotton wick without the disadvantages inherent in the latter wick, such as its charring, smoking, and production of odors.

15 In carrying out my invention I provide a non-combustible body or carrier provided on top with a flange or lip, and in contact with said body I place a cotton or other suitably-constructed fibrous wick, the upper end of 20 which rests beneath said flange or lip and in contact therewith. Said flange or lip is made porous or perforated to permit the passage through it of oil by capillary action, the oil being fed to said flange by said fibrous or cotton wick. The flame burns on the upper edge 25 of said flange or lip, and consequently does not reach the fibrous or cotton wick, the result being a pure white light without combustion of the wick material.

30 The invention further consists in the novel details of improvement and the combinations of parts that will be more fully herein-after set forth, and then pointed out in the claims.

35 Reference is to be had to the accompanying drawings, forming part hereof, wherein—

Figure 1 is a perspective view of the non-combustible body forming part of my improved wick. Fig. 2 is a vertical section 40 thereof. Fig. 3 is a corresponding view showing the fibrous oil-feeder in position on the non-combustible body. Fig. 4 is a perspective view of the body or carrier having a perforated flange or lip. Fig. 5 is a central section of a wick having double walls, forming a space to receive wicking material. Fig. 6 is a perspective view of a flat wick having two walls and a flat top. Fig. 7 is an end view of a rectangular wick-body having a 45 central space, and Fig. 8 is a perspective 50

view showing a flat wick-body having a flange and a porous wicking attached thereto.

In the accompanying drawings, in which similar letters of reference indicate corresponding parts in the several views, the letter A indicates a non-combustible wick body or carrier having a flange or lip *a* at its upper end, and B is a fibrous wicking material placed contiguous to said body A and resting against the under surface of the flange or 55 lip *a*.

The body A is preferably made of suitable clay and is also preferably made porous in the course of manufacture in any well-known or desired manner of making porous non-combustible bodies, or it may be a longitudinally-perforated body made in a well-known manner. The flange or lip *a* is also made porous or perforated, so as to serve to convey oil by capillary action to its upper surface from 60 the fibrous wicking B.

The wicking B may consist of the ordinary cotton wicking of commerce, or it may be of any other desired or suitable material which will serve to convey oil to the flange *a*.

75 I have shown the body A and flange *a* in a single piece of material, which is the preferred construction.

I have shown the body A in tubular form, which will serve with the well-known central-draft lamps or burners, being made of suitable size to pass over the central tube of the lamp. The fibrous wick B is also shown of tubular form fitted over the body A and lying in close contact therewith; but whether my 80 wick is made in tubular form or otherwise is not material to my invention so long as it embraces the characteristics of a body having a porous or perforated flange or lip and a fibrous wick in contact with said body and resting 85 against the under side of said flange.

90 By preference the body A extends down about to the bottom of the fibrous wicking B, so that both parts of the complete wick will be equally supplied with oil.

95 When the body A is made of porous material, as baked clay, it assists in conveying oil to the flange or lip *a*, and the crevice between the body A and wicking B also serves to carry up the oil by capillary action in addition to 100

the inherent capillary capacity of the fibrous wicking B.

In Fig. 5 the wick-body has double walls, forming a space b. The wicking B when placed in said space carries the oil to the flange or bridge a, while the double walls serve to thoroughly protect the wicking B.

In Figs. 6, 7, and 8 I have shown the body or carrier A as flat or rectangular, Fig. 6 showing two flat walls A A joined to the flange or bridge a, the sides or edges being open to permit the insertion of the wicking B between said walls. In Fig. 7 the body A is rectangular, and all four sides forming a central space b for the wicking B. In Fig. 8 a single flat plate A is shown having the flange a, and the wicking B may be secured thereto by any suitable means.

When my improved wick is in use the top 20 of the wicking B preferably extends slightly below the top of the outer metal tube of the lamp-burner, so that the flame will be prevented from reaching said wicking; but the flange a projects above said metal tube and 25 presents a proper surface for the flame which burns above the flange a. As the flange a does not consume, it will at all times be level on the top surface to produce an even flame, and there is therefore no necessity of trimming the wick. Much trouble and annoyance is therefore avoided.

My improved wick is practically indestructible under ordinary conditions of use, as the flange a is unaffected by the heat from the 35 flame. The flame burns uniformly and evenly, and as there is no burning of the wick smoking and the creating of odors are prevented and a perfect combustion of the oil takes

place and the qualities of the light are improved, because the body A and flange a become heated and volatilize a portion of the oil 40 or convert it into gas before it reaches the flame.

My improved wick is simple in construction, cheap to manufacture, and can be made 45 to fit almost any make of burner, suitable provision being made to enable the wick to be raised and lowered, which can be done in the burner the same as with an ordinary cotton wick.

I do not limit my invention to the details 50 of construction shown and described, as they may be varied without departing from the spirit of my invention.

Having now described my invention, what 55 I claim is—

1. A wick of inflexible or self-supporting incombustible porous material, as clay, comprising a wall serving as a support for a fibrous flexible wick, and an integral flange 60 serving as a continuation of the fibrous flexible wick, substantially as described.

2. A wick of inflexible or self-supporting incombustible porous material, as clay, comprising two parallel walls for inclosing and 65 supporting a fibrous flexible wick, and an integral flange upon said walls serving as a continuation of the fibrous flexible wick, substantially as described.

In testimony that I claim the invention 70 above set forth I affix my signature in presence of two witnesses.

STEPHEN B. MORSS.
